FIG. 1

INVENTOR
Aubrey M. Kennedy
BY *A. Lee Nelson*

ATTORNEY

UNITED STATES PATENT OFFICE.

AUBREY M. KENNEDY, OF NEW YORK, N. Y.

SOUND-NEUTRALIZING VENTILATOR.

Application filed January 20, 1926. Serial No. 82,418.

The object of the invention is to provide means for damping sound waves, particularly in connection with means for permitting a flow of air from one point to another as in the ventilation of rooms by air passing from the exterior of a building through window ventilators.

The invention will be described in the following specification and with reference to the accompanying drawings, in which—

Figure 1 is a fragmentary view of a window and window casing showing a ventilator, constructed in accordance with the invention, in rear elevation;

Figure 2 is a vertical section of the device on the line 2—2, Figure 3;

Figure 3 is a front elevation of the device illustrated in Figure 2, a central section of the device being broken away.

In my preferred form of structure, illustrated in Figures 1, 2 and 3, the device comprises parallel walls 1 and 2, a bottom wall 3, and a top wall 4, the said walls forming a rectangular casing in which the wall 1 is intended to be placed exteriorly of the room, the wall 2 facing the room. Wall 1 is provided with an inlet 1^x at its base, and the wall 2 is provided with an outlet 2^x at its top. The outlet 2^x is controlled as to size by a sliding plate 5 provided with an operating thumb piece 6, any suitable means being provided for latching the plate in a desired position.

Secured within the casing and extending longitudinally thereof is a deflector 7 formed as a plate which rests upon wall 3 and extends upwardly in a curve, the degree of the curve gradually increasing so as to provide an overhanging portion 7^x, the tip of which lies opposite, but spaced from the base of a second deflector 8 having a similarly formed curved upper extension 8^x. Extension 8^x is reversed in direction relatively to deflector 7. The tip of the curved extension 8^x of deflector 8 extends opposite to but spaced from the base of a third deflector 9, which deflector has an upper curved extension 9^x lying opposite but spaced from the fourth deflector 10. The curved extension 10^x of the fourth deflector has a tip which lies adjacent the outlet.

In the use of the construction above de-

scribed, air currents passing through the inlet 1^x and thence passing through the casing via outlet 2^x have movements which are indicated by the arrows. The said arrows also indicate the direction of travel of the sound waves which accompany the air currents. It will be seen that the sound waves are repeatedly directed against each other. In other words, the sound waves moving in given directions are repeatedly directed against sound waves moving in contra-directions, and the sound waves are destroyed by repeated mutual interference. When the sound waves strike deflector 7, they follow the inner curved wall of the latter in an upward path until the curved extension 7^x directs the waves downwardly and against incoming waves. By this mutual interference the sound waves are decreased in force. The sound waves following the upwardly moving current of air are again thrown back upon each other by the deflector 8 and this action is repeated by the deflectors 9 and 10. In Figure 2 four deflectors are employed, but the number may be varied in accordance with conditions to be met.

The casing is preferably lined with felt or other sound absorbing material, and when the deflectors are made of metal their surfaces may be covered with felt or other suitable sound wave absorbing material, this augmenting the sound neutralizing effect of the device.

Having described my invention what I claim and desire to secure by Letters Patent is as follows:

As a new article of manufacture, a device for permitting the passage of air from one point to another whilst neutralizing sound waves accompanying the same, which consists of a casing, an inlet at one face of the casing and an outlet at another face thereof, and a plurality of deflecting walls intermediate the inlet and outlet, each wall having an overhanging curved extension, the curvature being directed toward the inlet, and the deflecting walls being alternately opposed in the curvature of their extensions, as and for the purpose set forth.

In testimony whereof, I have signed my name to this specification.

AUBREY M. KENNEDY.
